UNITED STATES PATENT OFFICE.

HENRY V. STEVENS, OF EMPORIA, KANSAS.

DRAFT-REGULATOR.

1,391,348.

Specification of Letters Patent. Patented Sept. 20, 1921.

Continuation of application Serial No. 284,756, filed March 24, 1919. This application filed June 7, 1920. Serial No. 386,953.

To all whom it may concern:

Be it known that I, HENRY V. STEVENS, a citizen of the United States, residing at Emporia, in the county of Lyon and State 5 of Kansas, have invented certain new and useful Improvements in Draft-Regulators; and I do declare the following to be a full, clear, and exact description of the invention, such as will enable others skilled in the art 10 to which it appertains to make and use the same, reference being had to the accompanying drawings, and to the letters and figures of reference marked thereon, which form a part of this specification.

15 This application is a continuation of application Serial No. 284,756, filed by me on or about March 24, 1919 for "draft regulator."

The invention relates to draft control for 20 steam boiler furnaces and the invention primarily contemplates the provision of means for automatically controlling the velocity of the air passing through the fire-box of a furance in proportion to the pressure 25 sure maintained in the boiler or steam space.

For example, in locomotive practice, the combustion of the fuel is usually augmented by a forced draft consisting of a nozzle adjacent to the smoke stack operating 30 as an injector to cause a rapid displacement of air through the fire-box and while such a forced draft promotes rapid combustion of the fuel and consequently effects a relatively quick rise in steam generation, 35 it is also a wasteful means of maintaining the steam at a desired pressure.

I have provided means whereby the draft generated in the fire-box and consequently, the velocity of the moving air, may be 40 varied by variations in the steam pressure in the boiler; consequently, when the steam pressure in the boiler is high or has reached substantially its maximum, the velocity of the moving air will be relatively low and 45 inversely, when the steam pressure is low, the air velocity will increase to accelerate the combustion of the fuel and thereby bring the steam up to the desired pressure. By using a device embodying the principles 50 here involved, the rate of combustion may be proportioned in inverse ratio to the steam pressure in the boiler.

In the drawings,

Figure I is a side elevational view of a 55 locomotive boiler and furnace to which my invention is applied.

Fig. II is a transverse sectional view through a smoke box.

Fig. III is a side elevational view of a lubricating cup and part of a lubricating 60 pipe leading from the fountain to the control device.

Fig. IV is a longitudinal, sectional view through a draft regulator controller.

Fig. V is a top plan view of the draft 65 regulator.

Fig. VI is a reverse detail perspective view of the pinion and actuating bars for expanding the controller.

Fig. VII is a fragmentary detail view of 70 two of the controller sections, and

Fig. VIII is a sectional view on the line VIII—VIII of Fig. V.

Referring now to the drawings by numerals of reference:

1 designates a steam boiler as, for example, such as is applicable to locomotives, 2 being the fire-box and 3 the cab. Adjacent to the forward end of the smoke box is a smoke stack 4, beneath which is a draft controller 80 surrounding the ejector nozzle 31, common to this type of furnace, for effecting a forced draft to the fire-box 2. Leading from the dome 5 above the steam space of the boiler is a discharge pipe 6 which communicates 85 with a cylinder 7 having a constant pressure valve chamber 8 and a piston chamber 9, the two being divided by the partition 10 intermediate the ends of the cylinder. The spring chamber 8 may be by-passed by a 90 passage 11, best seen in Fig. IV, and in said chamber 8 is a spring 12, one end of which is adapted to abut against the partition 10 and the other end of which is adapted to bear against the piston valve 13 having 95 sliding movement to close off or permit communication between the pipe 6 and the bypass 11. Within the chamber 9 is a piston 14 having a piston stem or rod 15 terminating in a rack 16, guided in a guide 100 bracket 17, the rack having teeth 18 meshing with a gear 19 on a shaft 20 carried by the bracket 17, and the gear 19 meshing with a smaller gear 21 on a shaft 22, also carried by the wing 23 of the bracket 17. 105

The bracket 17 is preferably bolted to the upper end of the cylinder 7, as shown, the bolts 24 serving both as securing means for the bracket and for fastening the cylinder head 25 to the cylinder 7; therefore, when 110 it is desired to take the controller actuator apart for inspection or repairs, it will be

only necessary to remove the bolts and head 25.

Secured by a universal joint 26 to the shaft 22 is a connection 27, the other end 5 of which is secured by a universal joint 28 to a shaft 29 journaled in a ring frame 30 surrounding the jet nozzle 31 through which the forced draft passes to the stack 4. The effective port area of the nozzle 10 opening 32 from port 31 is adapted to be varied by an expansible and contractible ring consisting of a plurality of segments 33 in frame 30, these being hinged one to the other by joints 34, as best seen in Fig. 15 V. Two of the segments 33' and 33'' are provided with off-set ears 35 and 36 which are connected to the ears 37 and 38 on the respective sliding blocks 39 and 40, which are provided with rack teeth 41 and 42 to 20 mesh with the pinion 43 on shaft 29. The meeting edges of the segments 33' and 33'' are recessed as at 44 and 45 to receive a backing abutment 46 fast to the frame 30 so that the said segments will be held in 25 operative position with respect to the bars 39 and 40. In Fig. V, the ring-shaped valve device is shown in its constricted position to reduce the effective port area of the 30 ejector nozzle 31. The tongue and groove connections between the segments 33, shown in Fig. VII, permit enough lost motion to allow the ring to expand to increase the effective port area of the nozzle 31. The 35 abutment 46 constitutes a guide and an abutment for the segments 33' and 33'' so that the ring will be maintained in its proper relative position and to prevent displacement or binding of the racks 39 and 40, which are connected to said segments. Since 40 the ring is shown in its constricted position, in Fig. V with the pinion 43 meshing with the racks 39 and 40, it is obvious that when the pinion rotates in one direction, the racks 39 and 40, shown in Fig. VI, will move in 45 opposite directions to expand the ring and when the pinion is rotated in an opposite direction, the racks will be moved contrariwise to constrict the ring.

The smoke passing through the nozzle 31 50 has a tendency to leave deposits of carbon upon the ring seat and in the ring joints as well as to accumulate around the other operating parts. It, therefore, becomes desirable to remove or prevent the accumulation 55 of these carbon deposits and to this end I have provided means whereby a fluid under pressure, preferably steam, may be directed against the end of the nozzle and the moving parts to carry away any carbon 60 which has been deposited by the smoke.

Surrounding the segments of the ring which constitutes the draft controller is a lubricating space 47 having inlet ports 48 and 49 communicating with a steam pipe 65 50 leading from the fountain 51 and hav-

ing valves 52 and 53 on opposite sides of the valve lubricant-containing cup 54 whereby steam may be admitted from the fountain to the space 47 through the branch ports 70 48 and 49 to lubricate the ring. The forced draft nozzle will operate in the usual way but will be controlled by the mechanism above described.

For example, it will be assumed that the ring consisting of the segments 33 will be 75 normally restricted to reduce the effective port area of nozzle 32. Since the steam from the ejector nozzle will be escaping at a given rate, the constricted orifice will increase the velocity of the gaseous fluid (air) 80 passing through the fire-box and out through the stack, following the natural law of rates of flow. Therefore, the draft through the fire-box will be at the maximum for the given amount of steam issuing 85 from the ejector nozzle. When the products of combustion in the fire-box have raised the temperature of the water in the boiler and consequently generated steam at a sufficient pressure, say 180 pounds, the steam passing from dome 5 through pipe 6 to chamber 8 will raise the piston 13 against the action of the spring 12 until it passes the inlet to the by-pass port 11 whereupon the piston 14 will be raised, rotating 90 the gear 19 and through it, imparting movement to the gear 21 so as to rotate the link 27 and impart a rotary movement to the shaft 29, causing the pinion 43 to move the bars 39 and 40 in opposite directions and 95 100 as these are connected to the segments 33' and 33'', the ring will be expanded and thereby increase the effective port area of the nozzle 32, quickly cutting down the velocity of air and burnt gases passing to 105 the stack. As a result, the draft in the fire-box will be decreased and the combustible material will be consumed at a slower rate, permitting the steam pressure to be 110 maintained or allowing a drop in pressure 115 but not permitting the pressure to rise so that the steam will be blown off into atmosphere through the blow-off valve in the boiler and thereby permit a consumption of fuel to no advantage.

If there is a drop in pressure, the spring 12 will move the valve 13 toward the end of the cylinder 7, closing off communication between pipe 6 and by-pass 11, and permit the piston 14 to drop, the dropping of the piston being assisted by the weighted lever 55 on shaft 20 of gear 19, as best seen in Fig. IV. As the piston 14 drops and the gear 19 is rotated, a reverse rotation will be imparted to gear 21, causing the link 27 to be rotated in a reverse direction and thereby impart a movement to the shaft 29 and pinion 43, which will cause the bars 39 and 40 to be moved in a direction to bring the adjacent edges of the segments 33' and 120 125 130

33" one toward the other and thereby constrict the effective port area of port 32 and again increase the velocity of the draft to increase the consumption of the combustible material in the fire-box and thereby raise a steam pressure.

The alternate operations may continue in a well understood manner, it being obvious that the velocity of the draft will be in inverse ratio to the pressure in the boiler.

Under certain conditions the lubricator 54 may not be considered essential to the operation of the mechanism; for example, under certain conditions the lubricating cup 54 may be removed or the valve 54' may be closed so that only steam will be discharged through the ports 48 and 49 to prevent the accumulation of carbon, dust, dirt or other foreign matter.

If dry or super-heated steam is introduced through the pipe 50 and ports 48 and 49, the seat for the contractile ring or nozzle will be kept free of accumulations, as will also the hinged joints and adjacent parts.

Therefore, I may find it unnecessary in all instances to introduce a lubricant. The fluid, whether steam from the boiler or superheater, will be effective at all times without the necessity of employing a lubricant.

I, therefore, do not want to be limited to the use of lubricant for all purposes, the invention contemplating the admission of a fluid with or without the lubricant.

What I claim and desire to secure by Letters-Patent is:

1. In a draft regulator for steam boiler furnaces, a nozzle having an expansible and contractile ring at its outlet and to vary the effective port area of said nozzle, means responsive to boiler pressure for expanding and contracting said ring, and a boiler pressure actuated lubricating means for supplying lubricant to said ring.

2. In a device of the class described, an expansible and contractile tip for forced draft nozzles, and means for expanding and contracting said tip including a cylinder having two compartments, means for bypassing the steam around one compartment into the other, a piston in the latter compartment having a rack for operating gearing to expand and contract the tip, and a valve normally closing the inlet to the by-pass from an inlet port in the cylinder adjacent thereto.

3. In a draft regulator for steam boiler furnaces, an expansible and contractile member for engagement with the outlet end of a nozzle, means for operating said member comprising gearing, and means for operating the gearing comprising a rack for engagement with one of the gears, a counter-acting weighted lever connected to one of the gears, a piston on the rack, a cylinder in which the piston reciprocates, a second

cylinder in communication with the first named cylinder, and a pressure valve in the second mentioned cylinder controlling the passage of steam into the first named cylinder.

4. A draft regulator for steam boiler furnaces comprising an expansible and contractile member consisting of segments hinged together, means for expanding and contracting said member, a casing for said member, and a steam pipe leading into the casing to lubricate the same.

5. A draft regulator for steam boiler furnaces comprising an expansible and contractile member consisting of segments hinged together, means for expanding and contracting said member, a casing for said member, a steam pipe leading into the casing to lubricate the same, and a grease cup carried by the steam pipe.

6. In a draft regulator for steam boiler furnaces, a nozzle having an expansible and contractile portion to vary the effective port area thereof, and a boiler pressure actuated lubricating means for supplying lubricant to said expansible and contractile portion.

7. In a draft regulator for steam boiler furnaces, a nozzle having an expansible and contractile port area changing means, a tubular connection between the steam boiler and the means, and a lubricant container communicating with the tubular connection.

8. In a draft regulator for steam boiler furnaces, a nozzle having an expansible and contractile port area changing means comprising movable parts, and a fluid pressure pipe having a discharge end adjacent to the expansible and contractile port area changing means so as to discharge fluid pressure adjacent to the movable parts to remove accumulations therefrom.

9. In a draft regulator for steam boiler furnaces, a nozzle having an expansible and contractile port area changing means, and a conduit connected to the steam boiler and having a discharge end in proximity to the expansible and contractile port area changing means to direct fluid under pressure thereagainst.

10. In a draft regulator for steam boiler furnaces, a nozzle having an expansible and contractile port area changing means, means responsive to variations in boiler pressure for operating said port area changing means, and a fluid discharge port adjacent to the expansible and contractile port area changing means to direct fluid under pressure against the expansible and contractile port area changing means to maintain it free from accumulations of carbon and the like.

In testimony whereof I affix my signature.

HENRY V. STEVENS.
